UNITED STATES PATENT OFFICE.

ARTHUR W. LE BOEUF, OF WOONSOCKET, RHODE ISLAND, ASSIGNOR TO ELECTRIC COMPOSITOR COMPANY, OF NEW YORK, N. Y., A CORPORATION OF NEW JERSEY.

SLUG-DELIVERY MECHANISM FOR LINE-CASTING MACHINES.

1,112,628.

Specification of Letters Patent. Patented Oct. 6, 1914.

Application filed December 13, 1912. Serial No. 736,489.

To all whom it may concern:

Be it known that I, ARTHUR W. LE BOEUF, a citizen of the United States, residing at 208 Carrington avenue, city of Woonsocket, in the county of Providence and State of Rhode Island, have invented a certain new and useful Improvement in Slug-Delivery Mechanism for Line-Casting Machines, of which the following is a full, clear, and exact description.

This invention relates to means adapted for use in and as a part of a line casting machine for causing the type slugs after they are pushed out of the mold and between the trimming knives to be delivered and assembled in the galley.

The invention is especially contrived for use in a machine wherein the mold slot and the space between the trimming knives occupy substantially horizontal positions, and wherein the galley is considerably lower than said trimming knives. Under such conditions each slug comes from between the knives, printing edge first, lying on its side.

One object of this invention is to so receive and turn the slugs and deliver them into an inclined slug chute that the slugs in sliding down that chute will not have their printing characters injured, and will be delivered, resting on their bottom edges, on the galley floor.

Another object is to advance the slugs in the galley and prevent them from falling down or otherwise getting in the way of the slugs which are subsequently delivered into the galley.

The invention consists in the combinations of parts which produce and contribute to the production of these desired results, as hereinafter described, and definitely pointed out in the appended claims.

In the drawing, Figure 1 is a front elevation partly broken away of that part of a line casting machine which includes this invention. Fig. 2 is a side elevation thereof; Fig. 3 is a plan view; and Fig. 4 is a front end view of the slug packer P and the parts whereby it is operated. Fig. 5 is a side elevation showing the shelf D in the substantially horizontal position it must occupy when the slugs are pushed unto it, and showing the adjacent trimming knives in section.

The drawing shows, especially in Fig. 2, parts of the mold M, trimming knives

K¹ and ejector blade J in the relative positions they occupy before the ejector blade J begins its forward movement which pushes a slug S out of the mold slot and between the trimming knives. No attempt has been made to show the specific construction of these parts, because those familiar with this art well know how such parts may be constructed,—and the particular construction thereof is not material to this invention. The mold, to the extent shown, is like the mold shown and described in patent No. 982,834; and is movable in a horizontal path back and forth between the ejecting position, in which it is shown, and in which it normally comes to rest, and the casting position,—said movement being produced by the engagement of a rocking gear with a rack bar M¹, which forms the bottom member of the movable mold structure. The trimming knives K¹ may have the construction shown in prior Patent No. 998,619, or any other suitable construction.

As previously stated, the space between the trimming knives is horizontal, as is also the mold slot when the mold is in the slug ejecting position behind the trimming knives. When therefore the slug is pushed forward out of the mold slot it lies on its side with its printing edge forward, and it passes in this position between the trimming knives and onto a then horizontal tilting shelf D. This shelf is fixed in an approximately tangential position to a tubular rock shaft A which is mounted on a rearwardly projecting fixed stud F so as to be capable of rocking, and said shelf projects only a relatively short distance beyond said shaft on that side thereof which is adjacent to the chute C. Adjacent to the short left end of this shelf D is the upper receiving end of an inclined slug delivery chute C. The lower end of this chute is arranged to deliver the slugs onto the floor of the galley G. Having arrived at the galley the slugs S are moved to the right over against, and then along the galley with the column of previously delivered slugs in the galley. In the machine for which this mechanism, in the form shown, is especially adapted for use there is a single shaft A which may be caused to make one complete revolution at the will of the operator. In making this revolution it will cause the movements through their several cycles of all of the

parts which are concerned in the casting of the slug and its final disposition in the galley. More specifically, in so far as this mechanism has any relation to the present invention, the revolution of this shaft causes the mold to move in a horizontal path from the ejecting position in which it comes to rest, over to the casting position, and then back again. Also it causes the operation of the slug ejecting mechanism by which the slug is pushed from the mold between the trimming knives and onto the tilting shelf D. Also it causes said shelf to swing down to the horizontal slug receiving position and then to the nearly vertical slug delivery position in which it comes to rest. Also it causes the properly timed operation of the galley packer P in the slug packing direction, and then back to its normal position, as shown, just before the shelf D swings up to its vertical or slug dumping position. On the shaft A are several cams. One cam 'a' causes the rocking movement in both directions of the gear sector E which is loosely hung on shaft H. This sector engages with a gear b fixed to shaft B, and thereby turns the latter backward and forward. Another gear b' fixed to shaft B engages the rack bar m¹ which is the lower member of the horizontally movable mold structure M, and thereby the mold is moved. A lever N is loosely hung on this shaft B, and its upper end is connected by a link n with an arm d² fixed to the same rock shaft d to which the tilting shelf D is fixed. The lower arm of this lever N engages a cam a¹ on the shaft A. A spring d² shown as of the rat trap variety, turns shaft d, and through the described mechanism holds the lower end of the lever N in contact with the cam a¹. The galley packer P is a plate on the end of a belt arm p. This packer when in its normal position is a substantially forward continuation of the outer or left wall of the chute C, and serves also as the left wall of the galley. This arm p is rigid with a hub p¹ which embraces and is fixed to the rocking packer shaft R. A spring p² which presses to the left on an arm p³ fixed to hub p¹ acts to swing the packer to the left to its normal position, as shown, in which position it comes to rest because of the engagement with a fixture of a set screw p⁴, which screws through the downwardly extended arm p⁵ which is fixed to the packer hub.

An arm T is loosely mounted upon, but is yieldingly secured to the shaft R by means of a spring V which substantially surrounds and clasps the shaft and is fixed to the arm T by a screw t¹. The arm T carries a cross pin t, which passes through a longitudinal slot k in a link K. A set screw k¹ which screws into the end of this link and projects into the slot k is for engagement with the pin t when the link K has been drawn a

sufficient distance to the right. The right end of said link is connected with an arm h which is fixed to a rock shaft H. This shaft is rocked in one direction by a cam a² secured to shaft A, which engages with an arm h¹ fixed to shaft H, and is rocked in the opposite direction by a spring n². By adjusting the screw h¹, one may vary the throw of the packer in the packing direction. By adjusting the adjustment screw p⁴ one may vary the throw of the packer in the reverse direction.

The parts referred to are shown in the positions in which they come to rest. When shaft A begins to turn, the mold will be moved to the right to and held for a time in the casting position. Then it will be moved back to the ejecting position. Before it reaches this position the tilting shelf will be swung down to the slug receiving position, so as to receive the slug which will be pushed out of the mold while the latter is in the ejecting position. Just before shaft A completes its revolution shelf D is rocked into its slug dumping position, and this causes the slug to slide from said shelf into the chute, and thence onto the galley floor. The galley packer moves in the packing direction and then back to its normal position while shelf D is in its horizontal position. That is to say, the slug delivered to the galley as the result of one revolution of shaft A remains in the galley in the position it takes after it is discharged from chute C, until the shaft A has nearly completed its next rotation. But, as stated, before the tilting shelf D discharges a slug into the chute, the slug packer mechanism operated by cam a², moves through its cycle, thus carrying the previously delivered slug out of the way, and taking its own position at the left end of the galley.

Attention is called to the fact that the galley floor in front of the chute is in a little higher level than the remainder of said floor. The throw of the packer is adjusted so that it will move each slug far enough to the left to cause it to drop over the step at g² onto the lower portion of the floor. This in some degree decreases the chance that said slug may fall over to the left and get into the way of the next slug to slide down the chute.

Having described my invention, I claim:

1. In a line casting machine, the combination with side trimming knives arranged so that the opening between them is substantially horizontal, and a slug chute arranged in front of and adjacent to the opening between said trimming knives, of a slug receiving shelf arranged in front of said trimming knives and adapted to assume a substantially horizontal position below the opening between said trimming knives whereby a slug pushed between said trim-

ming knives will be delivered onto said shelf,—said shelf being tiltable about a horizontal forwardly extended axis, and means for tilting said shelf about said axis so as to 5 carry it from said horizontal position to an inclined position such as will cause the slug thereon to slide from the shelf into said chute, and vice versa.

2. In a line casting machine, the combination with side trimming knives arranged so 10 that the opening between them is substantially horizontal, and a slug chute arranged in front of and to one side of said trimming knives, of a forwardly extended and substantially horizontal rock shaft located below and in front of said trimming knives, a 15 slug receiving shelf secured to said rock shaft in a substantially tangential position, mechanism including a cam and a spring for 20 tilting said rock shaft so as to move the slug receiving shelf first to a horizontal slug receiving position, and then to an inclined slug discharging position and vice versa.

3. In a line casting machine, the combination with side trimming knives arranged so 25 that the opening between them is substantially horizontal, and an inclined slug chute arranged with its open upper receiving end in front of and adjacent to said trimming knives, a slug receiving shelf which is tilt- 30 able about a horizontal forwardly extended axis and adapted to occupy a substantially horizontal position below and in front of the opening between said trimming knives 35 and to be tilted into an inclined position whereby a slug thereon will be caused to

slide into the open upper end of said slug chute, a galley arranged to receive slugs discharged from the lower end of said slug chute, a galley packer which normally occupies a position in substantial alinement with the left wall of said chute whereby it serves as the left end wall of the galley, a single prime mover, and means intermediate of said prime mover and tilting shelf and 40 galley packer whereby said two parts are caused to move in proper synchronism.

4. In a line casting machine, the combination with side trimming knives arranged so 45 that the opening between them is substantially horizontal, and a slug receiving shelf which is tiltable about a horizontal axis which is located below the opening between the trimming knives and extends forwardly from said trimming knives, said shelf being 50 adapted to assume position such that its top surface is parallel with the openings between the trimming knives and a very short distance below the same, means for tilting 55 said shelf about its axis to and from the receiving position above described, and a slug chute having an open upper end located in a position such that when the shelf is tilted a slug which slides from the low end of said shelf will fall into the open 60 receiving mouth of said slug chute.

In testimony whereof, I hereunto affix my signature in the presence of two witnesses

ARTHUR W. LE BOEUF.
